US0D1087694S

(12) **United States Design Patent** (10) **Patent No.:** **US D1,087,694 S**
(45) **Date of Patent:** **** Aug. 12, 2025**

(54) **RETURNABLE BEAKER**

(71) Applicant: **FairCup GmbH**, Göttingen (DE)

(72) Inventor: **Sybille Meyer**, Göttingen (DE)

(**) Term: **15 Years**

(21) Appl. No.: **29/862,362**

(22) Filed: **Dec. 8, 2022**

(51) **LOC (15) Cl.** **07-01**

(52) **U.S. Cl.**

USPC **D7/510**; D7/531; D7/396.2

(58) **Field of Classification Search**

USPC D7/509, 523, 532, 540, 543, 500, 510,

D7/396.2, 392.1; D9/530; D3/202

CPC ... A47G 19/2205; A47G 19/23; A47J 41/024;

B65D 1/00

(57) **CLAIM**

The ornamental design for a returnable beaker, as shown and described.

DESCRIPTION

FIG. 1 is a front perspective view of my new design for a returnable beaker shown with lid attached in a configuration of use;

FIG. 2 is a front perspective view of my new design for a returnable beaker shown with lid removed for clarity of disclosure;

FIG. 3 is a front view thereof;

FIG. 4 is a back view thereof;

FIG. 5 is a right side view thereof;

FIG. 6 is a left side view thereof;

FIG. 7 is a bottom view thereof;

FIG. 8 is a top view thereof;

FIG. 9 is a top perspective view of a lid portion of my new design for a returnable beaker shown separately for clarity of disclosure; and,

FIG. 10 is a bottom perspective view of my new design for a returnable beaker shown with lid removed for clarity of disclosure.

1 Claim, 10 Drawing Sheets
